[57] **CLAIM**

The ornamental design for jaws for pliers, as shown and described.

DESCRIPTION

FIG. 1 is an isometric view from the upper right front of a pair of jaws for pliers showing our new design, in a partly open position, wherein the broken line illustration of a pair of handles is included for illustrative purposes and forms no part of the claimed design;

FIG. 2 is a top plan view of the jaws for pliers shown in FIG. 1;

FIG. 3 is a right side elevational view of a pair of jaws for pliers showing my new design, in a closed position;

FIG. 4 is a bottom plan view thereof;

FIG. 5 is a front end elevational view thereof;

FIG. 6 is a left side elevational view thereof; and,

FIG. 7 is a rear end elevational view thereof.
